UNITED STATES PATENT OFFICE.

CHARLES G. TIEFEL, OF ROCHESTER, NEW YORK.

FIGURE WHEELED TOY.

Application filed June 27, 1924. Serial No. 722,641.

This invention relates to improvements in 5 toys and has for its object the production of a toy comprising a toy animal figure which will be given a lifelike movement by operation of the toy, in connection with devices for imitating the sounds made by the feet of the animal.

In its preferred form the toy comprises a wheeled vehicle of any desired form with 10 a toy figure mounted thereon representing a horse and its rider. The figure is composed of parts relatively movable to represent the movements of the corresponding parts of a horse ridden at a gallop. Suitable connections are provided whereby 15 movement of the vehicle along a floor will effect the movements of the various parts. Associated with this figure is a noise-making device operated preferably in a timed relation with the movements of the parts to imitate the sounds made by the feet of a horse 20 moving at a run or gallop. As will be clearer later, instead of a figure composed of relatively movable parts a figure all in 25 one piece might be used. This will involve obvious changes in the manner of supporting the figure on the vehicle, but in other essentials the toy would be the same as in the preferred form. It will also be clear later 30 that instead of the figure of a horse and rider the figure of a horse only might be employed or, in fact, a figure representing some other animal. If the figure of some 35 other animal is used, corresponding changes can be made in the construction and operation of the noise-making device to make it give the results desired, that is, imitating sounds made by the feet of such an animal when moving at a certain gait.

40 Another object is to provide a construction whereby a toy having the various features herein referred to may be manufactured and assembled at a minimum cost without sacrificing strength and durability.

45 With these and incidental objects in view the invention consists in a novel construction and arrangement of parts, the features of novelty of which are pointed out in appended claims and a preferred form of embodiment of which is hereinafter described with reference to the accompanying drawings.

Of said drawings:

50 Fig. 1 is a side elevation of the complete toy.

55 Fig. 2 shows the construction and rela-

tions of the parts and the connections whereby movements of the parts are effected. It also shows the positions assumed by the parts at different points in their movements. 60

Fig. 3 is a section on the line 3—3 of Fig. 2.

Described in general terms the device in the accompanying drawings is a vehicle, preferably wheeled, adapted to be pushed along 65 the floor by a child. Mounted on this vehicle is a toy figure of a horse and rider composed of a plurality of parts which are relatively movable to represent the movements of the corresponding parts of the 70 horse and rider when moving. The mechanism for effecting and transmitting the movements to the parts of the figure is so designed that by certain variations herein-after referred to in the connections the extent of the movements and the consequent appearance of the moving object may be 75 varied. Included in the toy is a noise-maker for making sounds to imitate the sounds made by the feet of a horse. This may be 80 varied in construction, but in the illustrative embodiment it comprises a flexible strip which can be bent away from a co-operating flat surface and then released, allowing the strip to clap against the surface 85 as it returns to its normal position. This strip is bent or flexed and released by studs or similar parts carried by the adjacent wheel of the vehicle.

The wheel is also connected to one of the 90 parts of the figure, preferably one of the legs of the horse, and that leg is in turn connected with the other parts of the figure so that they all move in proper relation one with the others. The studs on the wheel 95 may be so spaced apart that they operate the noise-maker with reference to the movements of the parts of the figure so that the sounds occur at the proper points in said movements, although accuracy in this respect is not essential to make the toy interesting and amusing. 100

Described in detail and with reference to the drawings, the preferred form of the invention includes a handle or stick 10 by 105 which the device may be operated. Journaled at one end of the handle is a wheel 11. Instead of the handle 10 and a single wheel some other form of vehicle employing two or more wheels may readily be used. 110

Pivoted to the handle 10 are elements 12 and 13 representing respectively the fore

and hind legs of a horse. At their upper ends these elements are pivoted in the body 14 of the horse. The body may be shaped from a single sheet of material or it may, 5 as shown in the drawings, be formed of two parts representing the sides and fastened together by rivets. These rivets preferably are so placed and are so constructed that they serve as bearings or pivots for 10 the various elements in the body. As shown in Fig. 2 the upper end of the fore leg member is provided with a toothed segment 15, engaging teeth on a rack bar 16 slidably supported by the upper end of the 15 hind leg element 13 and provided with teeth 17, 18 and 19 meshing respectively with toothed segments on elements 20, 21 and 22 pivoted on rivets such as above mentioned. The element 20 represents the 20 tail of the horse and the element 21 the head and neck, while the element 22 represents substantially the upper half of the rider. The exterior of the body may be shaped or painted to represent the saddle 25 and the lower half of the rider as shown or, if it is desired to make the toy more elaborate the lower half of the rider may be made integral with the element 22. Strings or other material may be used as shown at 30 23 to represent reins.

Rigid with the fore leg element 12 is an 35 arm 24, to which is pivotally connected the one end of a link 25. The other end of the link is loosely supported by a stud or screw eccentrically mounted on the wheel 11. It 40 is apparent that the link might readily be connected to the fore leg element 12 above the point where that element is pivoted to the handle 10 and that by varying the point 45 where the link is connected either to the leg or to the wheel the extent of movement imparted to the leg may be varied. This will result in a corresponding variation in the movements of the parts as, by tracing 50 the connections through, it will be seen that the motion imparted to the leg is transmitted to the parts 20, 21 and 22, while the body 14 will have a to and fro movement on the legs. In Fig. 2 the extremes 55 of the movements of the various parts are indicated, one by the full outlines and the other by the dotted outlines. By comparing these two outlines it will be seen that when the wheel 11 is rotated the various parts of the figure go through movements representing in an attractive way the movements of the corresponding parts of a horse and rider moving at a lively gallop.

The device which has, for convenience, 60 been referred to as the noise-maker, may, as before stated be of various forms, but in the illustrative embodiment comprises a flexible strip 26 fastened at 27 to the top of the handle 10. Co-operating with the 65 free end of the strip are studs or similar

projections 28 on the side of the wheel 11. The side of the handle is cut away as shown at 29 to permit the studs to pass. As the wheel rotates the studs will successively engage the end of the strip 26 and carry it away from the upper surface of the handle 10. As the studs pass out of engagement with the strip the strip will snap back against the upper surface and make a clapping noise. The studs are so arranged on the wheel that at each rotation of the wheel the strip will be operated three times to produce sounds spaced apart in the way such sounds are usually spaced when imitating the sound of a running or galloping horse. It is, obviously, possible to shape the parts of the noise-maker or of their co-operating surfaces to get anything from a clicking sound for a small sized toy to a loud clapping noise where the toy is on a larger scale. While it is better to have these sounds occur in a timed relation with the movements of the parts, it will not detract from the attractiveness of the toy if this relation is not observed exactly and variations from this relation may be made without departing from the spirit of the invention.

While the form of embodiment herein shown and described is admirably adapted to fulfill the objects primarily stated, it is not the intention to be limited to this one form, as the invention is capable of various modifications and changes all coming within the scope of the claims which follow.

What is claimed is:

1. A device of the character described comprising a vehicle provided with a wheel, a toy figure of a horse and rider mounted on the vehicle and consisting of a plurality of parts relatively movable to simulate the movements of the corresponding parts of a horse and rider when the horse is running or galloping, a noise-maker operable to imitate the sounds made by the feet of a galloping horse, irregularly spaced apart studs moving with the wheel for actuating the noise-maker in a timed relation with the movements of the parts of the figure, and connections whereby rotation of the wheel will effect the above mentioned movements of the parts of the toy figure.

2. A device of the character described comprising a vehicle provided with a wheel, a toy figure representing a horse and rider, said figure being mounted on the vehicle and comprising a movable set of parts representing the legs, the head and neck and the tail of the horse and the body of the rider, a connection whereby rotation of the wheel of the vehicle will impart movement to one of the legs of the horse, connections comprising a toothed rack driven by said leg and co-operating with teeth carried by the rest of the parts of the figure to actuate them

to represent the movements of the corresponding parts of a moving horse and rider, a device operable to imitate the sounds made by the feet of a horse, and means carried by the wheel for operating said device.

3. A device of the character described comprising a handle, a wheel rotatably mounted on one end of the handle, members representing the legs of a horse pivoted at their lower ends to said handle, a member representing the body of a horse pivotally supported on the upper ends of the leg members, elements pivoted in the body to represent the neck and the tail of the horse and the body of the rider, a connection whereby rotation of the wheel will oscillate one of the leg members on its lower pivot, a toothed rack within the body of the horse connected for reciprocation by said oscillated leg, and toothed connections for transmitting the movements of the rack to the neck, tail and rider elements, devices mounted adjacent the wheel and operable to imitate the sounds made by the feet of a horse, and means carried by the wheel for operating said devices.

4. A device of the character described comprising a handle, a wheel rotatably mounted on one end of the handle, members representing the legs of a horse pivoted at their lower ends to said handle, a body member pivotally supported on the upper ends of the leg members, a rack, teeth integral

with one of the leg members and meshing with teeth of the rack, elements pivoted in the body to represent the neck and tail of the horse and the body of the rider, said elements being provided with teeth meshing with teeth of the rack, connections whereby rotation of the vehicle wheel will oscillate one of the leg members on its lower pivot, devices mounted adjacent the wheel operable to imitate the sounds of the feet of a horse, and means moving with the wheel for operating said devices.

5. A device of the character described comprising a handle, a wheel rotatably mounted on one end of the handle, members representing the legs of a horse pivoted at their lower ends to said handle, a member representing the body of a horse pivotally supported on the upper ends of said leg members, elements pivoted in the body to represent the neck and the tail of the horse and the body of the rider, a connection whereby rotation of the wheel will oscillate one of the leg members on its lower pivot, a toothed rack within the body of the horse connected for reciprocation by said oscillated leg, and toothed connections for transmitting movements of the rack to the neck, tail and rider elements.

In testimony whereof I hereto affix my signature.

CHARLES G. TIEFEL.
